CLAIM

(21) Appl. No.: **29/243,987**

The ornamental design for an audio/video accessory for electronic device, as shown and described.

(22) Filed: **Dec. 5, 2005**

DESCRIPTION

(51) **LOC (8) Cl.** **14-03**

FIG. 1 is a perspective view of the audio/video accessory for electronic device according to the present invention.

(52) **U.S. Cl.** **D14/126**

FIG. 2 is a front view of the audio/video accessory for electronic device of FIG. 1.

(58) **Field of Classification Search** D14/125,
D14/126, 127, 128, 129, 133, 374, 375, 376;
348/836, 838, 180, 184, 325, 739; 248/917-924;
345/104, 133, 156, 168, 87, 173; 314/12;
349/1, 2, 11

FIG. 3 is a rear view of the audio/video accessory for electronic device of FIG. 1.

See application file for complete search history.

FIG. 4 is a right side view of the audio/video accessory for electronic device of FIG. 1.

(56) **References Cited**

FIG. 5 is a left side view of the audio/video accessory for electronic device of FIG. 1.

U.S. PATENT DOCUMENTS

FIG. 6 is a top view of the audio/video accessory for electronic device of FIG. 1; and,
